UNITED STATES PATENT OFFICE

ADOLPH RYDQUIST, OF ROCHESTER, NEW YORK.

PAPER-DISPENSING APPARATUS.

1,186,685.

Specification of Letters Patent. Patented June 13, 1916.

Application filed August 24, 1912. Serial No. 716,850.

To all whom it may concern:

Be it known that I, ADOLPH RYDQUIST, of Rochester, in the county of Monroe and State of New York, have invented certain new and useful Improvements in Paper-Dispensing Apparatus; and I do hereby declare the following to be a full, clear, and exact description of the same, reference being had to the accompanying drawings, forming a part of this specification, and to the reference numerals marked thereon.

The present invention relates to a paper dispensing apparatus, with particular reference to the type of device embodying a paper feeding roll which is normally locked against movement and adapted to be unlocked by a manual operation to permit a limited amount of paper to be drawn from the machine until the feeding roll is automatically relocked, and it has for its object to provide a novel and simple arrangement of parts for accomplishing this end.

A further object of my invention is the arrangement of improved means for preventing reverse movement of the feeding roll, which often results in clogging the machine.

Another object is to provide novel paper engaging devices operating in conjunction with the paper feeding roll, so as to pick up the paper and guide it properly to the discharge opening of the machine.

To these and other ends the invention consists in certain improvements and combinations of parts all as will be hereinafter more fully described, the novel features being pointed out in the claims at the end of the specification.

In the drawings: Figure 1 is a front view of a paper dispensing apparatus constructed in accordance with a preferred embodiment of my invention; Fig. 2 is a side elevation of the same; Fig. 3 is a view similar to Fig. 2, showing the cover lowered to permit adjustment of the paper roll; Fig. 4 is an enlarged detail view of the locking mechanism on the interior of the cover; Fig. 5 is a sectional view on the line $x-x$ of Fig. 4, showing the position of the key for opening the casing; Fig. 6 is a transverse, vertical sectional view, taken substantially in the direction of line $a-a$ of Fig. 8; Fig. 7 is a vertical sectional view on the line $y-y$ of Fig. 6; Fig. 8 is a horizontal sectional view on the line $b-b$ of Fig. 6; Fig. 9 is a sectional view on the line $z-z$ of Fig. 8, showing

the parts in normal position for locking the paper feeding roll against movement; Fig. 10 is a similar view, showing the releasing member moved with relation to the paper feeding roll so as to actuate the locking device to permit movement of the feeding roll; Fig. 11 is a sectional view taken substantially on the line $c-c$ of Fig. 9, and Fig. 12 is a sectional view taken substantially on the line $d-d$ of Fig. 8.

Similar reference numerals throughout the several figures indicate the same parts.

In the embodiment of the invention illustrated, the parts are housed within a casing comprising a base 1 to which is secured the slotted side walls 2 arranged to receive the ends 3 of a paper holding roll 4. The casing is closed by a suitable cover 5 pivotally connected to the side walls 2, and adapted to be held in engagement with the base 1 by locking means that I will describe hereinafter.

The paper, arranged on the paper holding roll 4, is engaged and fed by means of a paper feeding roll which includes the rotary sleeve 6 carrying the roll sections 7, the peripheries 8 of which preferably comprise sand paper or other suitable rough material. Fixed on the sleeve 6 is a gear wheel 9 from the side of which extends an abutment 10, for a purpose to be mentioned presently, said abutment preferably projecting to a point within the adjacent roll section 7, as shown in Fig. 11. The sleeve 6 rotates on the bearings 11 and 12, respectively, the latter preferably embodying a rotary shaft carrying a hand wheel 13 at its outer end, for a purpose that will now be described.

Arranged for coöperation with the paper feeding roll are paper engaging devices, which, in the present embodiment comprise a series of metal disks 14 mounted on the tubular shaft 15, and provided with sharpened teeth 16. The disks are arranged at suitable intervals and separated by means of spacing blocks 17, the parts being held in assembled position by means of longitudinal rods 18. The tubular shaft 15 is rotatably supported on bearings 19 carried by the side walls 2 and fixedly mounted on the shaft is a gear wheel 20 which is arranged to engage the aforesaid gear wheel 9 and to obtain movement therefrom.

The paper feeding roll is arranged to be normally locked against movement, and to this end there is provided a locking member, embodying a cam plate 21 loosely mounted

on the shaft 15 and carrying a forwardly projecting nose 22 arranged to engage the abutment 10 on the paper feeding roll. Immediately beneath the nose 22 of the cam plate, the latter is provided with a cam surface 23 arranged to be engaged by a releasing member which has a limited movement with relation to the paper feeding roll, and in the present embodiment comprises a disk 24 fixed upon the shaft 12 and having an inwardly extending projection 25 arranged to engage said cam surface 23. Thus, in the operation of the machine, the parts are normally in the position shown in Fig. 9, the cam plate 21 being engaged with the abutment 10 and locking the paper feeding roll against movement. When it is desired to withdraw paper from the machine, the hand wheel 13 is turned sufficiently to move the projection 25 to the position shown in Fig. 10, causing the cam plate 21 to be raised out of engagement with the abutment 10 and permitting the paper feeding roll to move. The paper may then be withdrawn during the revolution of the paper feeding roll and until the abutment 10 again reaches the cam plate 21, whereby further movement is prevented. It will be noted that the gear wheel 9 is cut away to permit the projection 25 to 25 extend therethrough and to have the required movement relatively to the paper feeding roll.

The cam plate 21 is provided with a series of ratchet teeth 26 which are adapted to engage the notches on the gear wheel 20, said cam plate being held in frictional engagement with the gear wheel 20 by means of the coiled spring 27. The gear wheel 20 rotates normally in an anti-clockwise direction, and thus tends to move the cam plate into engagement with the abutment 10. If an attempt is made to reverse the movement of the paper feeding roll, it will cause a reverse movement of the gear wheel 20 and of the cam plate 21 until the latter engages the upwardly extending wall 28 of the casing and thereupon the teeth 26 engage the notches of the gear wheel, and lock the same against further reverse movement. Thus only a very slight reverse movement of the paper feeding roll is possible, before the parts become securely locked. The upwardly extending wall 28, before referred to, extends to a point slightly above the center of the shaft 15, and is slotted, as shown, to permit the passage of the toothed disks 14. This slotted wall forms a most efficient guide for the paper and in conjunction with the toothed disks 14, effectually prevents the paper from clogging within the casing.

The paper roll is normally held in engagement with the paper feeding roll, as already described, and to this end, there are provided a pair of pivoted members 29 arranged in the sides of the cover 5, engag-

ing the ends 3 of the paper holding roll when the cover is closed, and forcing the same downwardly toward the paper feeding roll. In order to indicate the amount of paper within the casing, the sides of the cover 5 are slotted, as designated at 30, and extending through the slots 30 are suitable indicators 31 which project from the pivoted members 29. The pivoted members 29 are held in engagement with the paper holding roll by means of suitable springs 32 connected to the members 29 and to the casing, as shown. Thus, as the paper is exhausted from the paper holding roll, the members 29 will move downwardly under the action of springs 32 and cause the indicators 31 to move toward the lower ends of the slots 30.

The cover of the casing may be held in engagement with the base in any suitable manner, but I prefer to employ the locking means disclosed in the present embodiment, and which comprises a headed projection 33 carried by the base 1 and arranged to be engaged by a spring hasp 34 mounted on the cover 5. The hasp 34 is provided with the opening 35, and with a depression 36 at its outer end, which engages the headed projection 33, as shown in Fig. 6. The movement of the hasp 34 is limited by means of a plate 37 secured to the cover and having a flange 38 projecting toward the hasp. The cover is provided with a suitable key opening 39 arranged in alignment with the opening 39 in the hasp, and the plate 37 is provided with a circular opening 40 to receive the end of the key, and limit the movement of the latter, as shown in Fig. 5. The key is inserted until it abuts the plate 38, and is then turned, to engage the surface of the hasp and move the same out of locking engagement with the headed projection 33. The key can only be turned a limited distance, determined by the flange 38 on the plate 40. This affords an extremely simple and effective lock, which requires the use of a key constructed particularly for the purpose, and can only be opened with considerable difficulty without an authorized key.

I claim as my invention:

1. In a paper dispensing apparatus, the combination with a paper feeding roll, of a rotary shaft arranged in spaced relation to the paper feeding roll, paper engaging devices mounted on said shaft, a gear wheel carried by the paper feeding roll, a gear wheel fixed on said rotary shaft and in engagement with the first mentioned gear wheel, a plate loosely arranged on the shaft and provided with ratchet teeth engaging the notches of the gear wheel on said shaft, means for limiting the rotary movement of said plate, and a spring effecting engagement of the plate with the gear wheel.

2. In a paper dispensing apparatus, the combination with a paper feeding roll, of a

rotary shaft arranged in spaced relation to the paper feeding roll, paper engaging devices mounted on said shaft, a movable locking member loosely arranged on said shaft 5 and normally in engagement with the paper feeding roll, a manually controlled member adapted to move the locking member out of engagement with the paper feeding roll, a gear wheel carried by the paper feeding roll, 10 a gear wheel fixed on said rotary shaft and in engagement with the first mentioned gear wheel, the aforesaid locking member having ratchet teeth engaging the notches of the gear wheel on the shaft, means for limiting the rotary movement of the locking member, 15 and a spring effecting engagement of the locking member and the gear wheel.

ADOLPH RYDQUIST.
